DESIGN FOR A HAIR DRIER OR THE LIKE

Marshall H. Frisbie, Hamden, Conn., and Harry S. Preble, Jr., Jackson Heights, N. Y., assignors to The A. C. Gilbert Company, New Haven, Conn., a corporation of Maryland

Application August 22, 1940, Serial No. 94,554

Term of patent 7 years

To all whom it may concern:

Be it known that we, Marshall H. Frisbie and Harry S. Preble, Jr., citizens of the United States, residing, respectively, at Hamden, in the county of New Haven and State of Connecticut, and of Jackson Heights, in the county of Queens and State of New York, have invented a new, original, and ornamental Design for a Hair Drier or the like, of which the following is a specification, reference being had to the accompanying drawing, forming part thereof.

Figures 1, 2 and 3 are, respectively, a perspective view, a top plan view and a view in side elevation, of a hair drier or the like showing our new design.

We claim:

The ornamental design for a hair drier or the like, substantially as shown.

MARSHALL H. FRISBIE.
